JEWELRY CLASP

Harry Borden, Brooklyn, N. Y.

Application January 15, 1941, Serial No. 374,418

6 Claims.

(Cl. 24—71)

This invention relates to clasps intended for use in connection with the wrist bands of wrist watches, bracelets or other similar articles.

More particularly, the invention relates to the type of clasp wherein a plurality of hingedly connected links are pivotally attached to a casing in which they are nested in overlying relationship while the clasp is in its closed condition and which are swung out of the casing to extended position when it is desired to elongate the effective length of the wrist-encircling band of which the clasp forms a part. The object of the present invention is to provide, in a clasp of the general structure above described, locking means by which inadvertent opening or extension of the several links or connected elements of the clasp is effectively prevented.

The invention contemplates the provision of a casing in which the parts of the clasp are housed, several of said parts consisting of hinged links pivoted at one end of the casing; a slideable link is movable in and out of the casing and interengaging elements are provided on one of the hinged parts and on the slideable link, said interengaging parts being so disposed in co-operative relationship that they retain the hinged parts nested within the casing while the slideable link is retracted or partly retracted therein, and become disengaged and permit swinging movement of said parts out of the casing when the slideable link has been moved to the limit of its movement out of the casing.

In the accompanying drawing, forming a part hereof, Fig. 1 is a front elevational view of a clasp made in accordance with the invention; Fig. 2 is a similar view, showing the parts of the clasp in open or extended position; Fig. 3 is a rear view of the clasp in open or extended position; Fig. 4 is a sectional view on the line 4—4 of Fig. 1, looking in the direction of the arrows; Fig. 5 is also a longitudinal sectional view through the clasp, showing the same in partly open position; Fig. 6 is a sectional view on the line 6—6 of Fig. 1, looking in the direction of the arrows; Fig. 7 is a sectional view on the line 7—7 of Fig. 3, looking in the direction of the arrows; and Fig. 8 is a rear view of the casing, the slideable link and ratchet means therefor.

In the drawing, 1 indicates the body portion or main element of the clasp, the same being in the form of a substantially rectangular, slightly curved, casing composed of a front 2 and top and bottom walls 3 and 4. Pivoted between the top and bottom walls on the pintle 5 is a link member 6 in the form of a rectangular open frame, provided with the central opening or aperture 7. The opposite end of the outer link member 9 is provided with a loop portion 10 or other connecting means by which this end of the link member may be attached to one end of the wrist

band or bracelet, a portion of which is indicated at 11.

The outer link member 9 is composed of two parts, namely, an outer portion 12 and an inner overlying plate 13, the latter plate being secured over the inner face of the outer portion 12 by means of the several bent-over lugs 14, clearly seen in Fig. 2. When the clasp is in its closed position, as shown in Figs. 1, 4 and 6, the two link members 6 and 9 are nested within the casing 1 in overlying relationship or in closed position and means to be described are provided for retaining said members in such closed position.

Provided on the plate portion 13 is a projecting elongated flange 15 extending longitudinally of the link member 9 and preferably forced out of the body of the plate portion 13 and directed inwardly and upwardly, as clearly seen in Fig. 6 so that it extends towards the inner face of the front plate 2 of the casing 1 when the clasp is in its closed position. The opening 7 formed in the link member 6 allows the flange 15 to project through said link member to engage behind a lug 16 provided on a slideable link 17 mounted within the casing and movable in and out of that end of the casing 1 opposite to that where the pivot 5 is located. The slideable link 17 is formed at one end with a loop portion 18 or other suitable part for engagement with the end 11a of the wrist band or bracelet. The slideable link 17 is restrained from sliding movement in a direction out of the casing by means of a pawl 19 engaging with ratchet teeth 20 formed on the inner edge of one of the side bars 21 of the slideable link 17. The pawl 19 consists of an inturned end of a spring arm 22 comprising part of a substantially U-shaped member 23 secured between the top and bottom walls 3 and 4 of the casing and providing a guide-channel between it and the front wall 2 of the casing within which the link 17 is slideable. A lug 24 formed on the resilient arm 22 extends through an opening provided in the wall 3 of the casing, said lug constituting a finger-engaging element by which the resilient arm 22 can be depressed, as shown in Fig. 8, to release the pawl 19 from engagement with ratchet teeth 20 and permit the slideable link 17 to be shifted out of the casing to the limit of such movement as shown in Figs. 2, 3 and 5 at which time the lug 16 abuts against cross bar 25, provided on member 23, and acts as a stop to prevent further outward sliding movement of the slideable link. The side bar 26 of the member 23 is formed with a lug 27 which extends through the wall 4 and serves to hold the member 23 against shifting movement out of the casing.

The clasp is shown in its open position in Fig. 3 wherein it will be seen that the slideable link 17 is extended out of the casing 1 to the limit of its outward movement, at which time the lug

16 is in abutment with the bar 25 of the member 23. The link members 6 and 9 have been swung out of the casing, so that the wrist band or bracelet is extended to its fullest degree and may now be slipped over the hand. To tighten the band around the wrist, the link members 6 and 9 are first folded upon each other, as shown in Fig. 5 and then nested within the casing 1. When this is done, the flange 15 on plate 13 is projected through opening 7 in link member 6. It will be noted that at this time, and while the slidable link 17 is fully extended, the lug 16 carried by it is positioned beyond the end of the flange 15, or in the opening 29 in the plate 13, clearly seen in Fig. 2. Next, the slidable link 17 is manually slid inwardly within the casing to the required extent to enable the wrist band or bracelet to properly fit the wrist, the ratchet mechanism permitting this inward sliding movement, and as soon as the link 17 is slid inwardly, the lug 16 will engage behind the flange 15. Since the pawl 19 will prevent outward sliding movement of the link 17 unless the lug 24 is depressed, it will be obvious that links 6 and 9 will be prevented from swinging movement out of the casing by the engagement of lug 16 with the flange 15 as clearly seen in Fig. 6. To open the clasp, the lug 24 is depressed and slidable link 17 is moved out of the casing 1 to the limit of such extended movement, at which point lug 16 will have moved beyond the end of the flange 15 and the link members 6 and 9 can then be swung to open position.

What I claim is:

1. A clasp of the character described comprising a casing, one end of said casing being pivotally attached to a pair of hingedly connected links, said links being adapted to be either disposed within said casing in overlying relationship, or swung outwardly in extended position out of the casing, a slidable link member in the form of a frame, movable in or out of the casing, ratchet means for normally restraining movement of said slidable link member out of the casing, and interengaging parts on said slidable link member and one of the hinged links, said parts engaging within the frame-like link member and remote from the outer edges thereof whereby the links are retained in overlying relationship within the casing until the slidable link member is manually moved to its extended position out of the casing.

2. A clasp of the character described comprising, a casing, two hingedly connected link members pivotally attached to the casing and adapted to be nested within the casing in overlying relationship, one of said link members being centrally apertured, a slidable link mounted in the casing and capable of movement to an extended position out of the casing, manually releasable means for holding the slidable link in any selected position of adjustment relative to the casing, said link having a projecting lug entrant through the aperture in one of the link members, one of the hinged link members being provided with a flange over which said lug extends when said lug extends through said aperture to thereby hold the link members against movement out of the casing while the slidable link is disposed within the casing.

3. A clasp of the character described comprising, a casing, an apertured link member pivot-

ally attached at one end of said casing, a second link member pivotally attached to said first link member, both of said link members being capable of swinging movement into an overlying position within the casing, a slidable link movable in and out of one end of the casing, ratchet means for restraining said slidable link against movement out of the casing, and interengaging parts on the slidable link and on the second link member and located in engagement within the aperture in the first link member for holding the link members against pivotal movement, said interengaging parts being released from engagement with one another only when the slidable link is located at the limit of its movement out of the casing.

4. A clasp of the character described comprising, a casing, a link member pivotally attached at one end of said casing, a second link member pivotally attached to said first link member, both of said link members being capable of swinging movement into an overlying position within the casing, a slidable link in the form of a frame movable in and out of one end of the casing, ratchet means for restraining said slidable link against movement out of the casing, the slidable link having a rearwardly extended lug located remotely of its longitudinal edges and directed inwardly therefrom, one of the link members having a lengthy projecting flange disposed behind said lug when the slidable link is at least partly retracted within the casing, and disengaged from said lug when the slidable link is extended to the limit of its movement out of the casing.

5. A clasp of the character described comprising, a casing, two hingedly connected links pivotally attached to the casing and adapted for movement into overlying position within the casing, a slidable frame-like link mounted in the casing and adapted for movement into or partly out of the same, and means carried by said slidable link remote from its edges for engaging the end one of the link members while said link and link members are disposed within the casing for holding the link members against swinging movement out of the casing, the link located between the casing and the end link being provided with a central aperture through which the engaging means carried by the slidable link is brought into engagement with the end link.

6. A clasp of the character described comprising, a casing, a pair of hingedly connected link members pivotally attached to one end of the casing and adapted to be swung into said casing in overlying position, one of said link members being in the form of an open frame, the other link member having a projecting flange directed through the frame and toward the front of the casing, a slidable link movable longitudinally of the casing and in and out of one end thereof, means for regulating and limiting the extent of projection of said slidable link out of the casing, a lug provided on said slidable link, said lug engaging the flange within the opening in the frame and holding the link members against swinging movement, said lug disengaging from the flange when the slidable link is fully projected out of the casing to permit the link members to be swung out of the casing.

HARRY BORDEN.
